Primary Examiner — Ian Simmons*Assistant Examiner* — Richelle G Shelton*(74) Attorney, Agent, or Firm* — Craig A. Deutsch(57) **CLAIM**

The ornamental design for a facepiece, as shown and described.

DESCRIPTION

FIG. 1 is a front perspective view of the new design for a facepiece.

FIG. 2 is a front view thereof;

FIG. 3 is a back view thereof;

FIG. 4 is a top view thereof;

FIG. 5 is a bottom view thereof; and,

FIG. 6 is a right side view thereof, the left side view being a

mirror image thereof.

The broken line showing of a mask is included for the purpose of illustrating environment and forms no part of the claimed design. The shading is provided to illustrate contour only and is not an indication of surface texture or sheen.
